CLAIM

The ornamental design for an end joint flashing, as shown and described.

DESCRIPTION

FIG. 1 is a front, top, right side isometric view of a first embodiment of an end joint flashing showing my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and

FIG. 7 is a rear elevation view thereof;

FIG. 8 is a front, top, right side isometric view of a second embodiment of the end joint flashing showing my new design;

FIG. 9 is a top plan view thereof;

FIG. 10 is a bottom plan view thereof;

FIG. 11 is a left side elevation view thereof;

FIG. 12 is a right side elevation view thereof;

FIG. 13 is a front elevation view thereof; and,

FIG. 14 is a rear elevation view thereof.

The broken lines shown in the figures represent portions of the end joint flashing that form no part of the claimed design.

1 Claim, 10 Drawing Sheets
